UNITED STATES PATENT OFFICE

164,566

DISPLAY CONTAINER OR SIMILAR ARTICLE

Morris Friedman, Brooklyn, N. Y.

Application October 30, 1950, Serial No. 12,777

Term of patent 7 years

(Cl. D80—5)

To all whom it may concern:

Be it known that I, Morris Friedman, a citizen of the United States, whose post-office address is 515 Alabama Avenue, Brooklyn, county of Kings, and State of New York, have invented a new, original, and ornamental Display Container or Similar Article, of which the following is a specification, reference being had to the accompanying drawings, forming a part thereof.

Fig. 1 is a front elevational view of the display container or similar article in closed position, showing my new design;

Fig. 2 is a side elevational view of the same;

Fig. 3 is a plan view of the same;

Fig. 4 is a front elevational view of the display container or similar article in open position; and

Fig. 5 is a back elevational view of the display container or similar article in closed position.

I claim:

The ornamental design for a display container or similar article, as shown.

MORRIS FRIEDMAN.
